UNITED STATES PATENT OFFICE.

EDWARD F. PRESBREY, OF PROVIDENCE, RHODE ISLAND, ASSIGNOR TO HAMILTON & HAMILTON, JR., OF PROVIDENCE, RHODE ISLAND, CO-PARTNERS.

SLIDE-BRACELET.

No. 824,309.

Specification of Letters Patent.

Patented June 26, 1906.

Application filed April 18, 1905. Serial No. 256,310.

To all whom it may concern:

Be it known that I, EDWARD F. PRESBREY, a citizen of the United States, residing at Providence, in the State of Rhode Island, 5 have invented a new and useful Improvement in Slide-Bracelets, of which the following is a specification.

My invention consists in the improved construction of the locking means for the two 10 parts of the bracelet, whereby a durable and efficient locking means is provided, as herein-after set forth.

In the accompanying drawings, Figure 1 represents a side view of a slide-bracelet provided with my improvement, a portion of 15 both members being broken away to show the improved locking means. Fig. 2 represents the same when the parts of the bracelet are pulled apart preparatory for placing the 20 bracelet upon the wrist of the wearer. Fig. 3 represents an enlarged detail sectional view of the improved locking means when the parts of the bracelet are closed, as in Fig. 1. Fig. 4 represents an inner side view of the 25 locking means, as shown in Fig. 3. Fig. 5 represents an outer side view of the same. Fig. 6 represents a detail sectional view of the locking means when the parts of the bracelet are separated, as in Fig. 2. Fig. 7 represents 30 a transverse section taken on the line 7 7 of Fig. 3.

In the drawings, A represents one hollow member, and B the other hollow member, of a slide-bracelet, the said members being connected to each other by means of the flexible 35 German-silver slide-strips CC, one of the ends of which is soldered within the cavity D of the member A, the other end being provided

with the indentation a, which is adapted to pass onto and engage with the corresponding 40 elevation b, struck up in the projecting end c of the curved guide E, which serves to guide the opposite edges of the slide-strip C, as shown in Fig. 6, the said slide-strip constituting the resilient member. The guide E is 45 provided with the slot d, and the slide-strip C is provided with the struck-up projection e, which enters the slot d and serves to limit the outward and inward movement of the 50 said slide-strip. The curved guide E is also 50 provided with the head f, having an elongated perforation g, through which the slide-strip C is made to loosely pass, and the said guide E may be secured within the cavity of the bracelet member B by suitable means. 55

I claim as my invention—

In a slide-bracelet, the combination of the hollow members of the bracelet, with the flexible slide-strips, each secured at its outer end to the end of a bracelet member, and provided at its opposite inner end with the struck-up engaging depression, and with the struck-up elevation, with the curved guides, secured within the cavity of the bracelet member, and each provided, with a struck-up 60 elevation, adapted to engage with the depression of the guided flexible slide-strip, and also provided with the slot adapted to receive the stop elevation which serves to limit the outward and inward movement of the 65 flexible slide-strip, substantially as described. 70

EDWARD F. PRESBREY.
